United States Patent Office.

JAMES S. LESTER AND PERRIN H. CARDWELL, OF KNOXVILLE, TENNESSEE.

Letters Patent No. 81,516, dated August 25, 1868.

IMPROVEMENT IN SHOES.

The Schedule referred to in these Letters Patent and making part of the same.

TO ALL WHOM IT MAY CONCERN:

Be it known that we, JAMES S. LESTER and PERRIN H. CARDWELL, of Knoxville, in the county of Knox, and in the State of Tennessee, have invented certain new and useful Improvements in Shoes; and do hereby declare that the following is a full, clear, and exact description thereof, reference being made to the accompanying drawings, and to the letters of reference marked thereon.

The nature of our invention consists in the peculiar mode of cutting the front or vamp and side pieces for a shoe, forming the shoe of three pieces, thereby dispensing with the usual mode of crimping the front or vamp. Also in closing the quarters or side pieces in the back, from the bottom to the top of the counter, and leaving the rest of the back open from the top of the counter to the top of the shoe or garter, and fastening the same either by lace, buckle, button, or any other suitable fastening.

By this arrangement it is made easy to measure the foot to secure a perfect fit, and also effects a great saving in time and leather or other material used, as well as dispensing with the use of rubber.

In order to enable others skilled in the art to make and use our invention, we will proceed to describe its construction and operation, referring to the annexed drawings, which form a part of this specification, and in which—

Figures 1 and 2 are side views of the shoe, and

Figure 3 is a plan view of the front or vamp of the shoe.

Figures 4 and 5 are side views of the quarters or side pieces.

A represents the front or vamp of the shoe cut, as shown in fig. 3, and slit open from *a* to *b*. It is then bent over the last, the edge from *a* to *b* forming, with the edge from *h* to *i* on the side piece C, which is cut, as shown in fig. 5, the front seam, as shown in fig. 2. The edges *b* to *c* and *c* to *f* form, with the edges *i* to *h* and *h* to *l*, the side seam, as shown in same figures.

The side piece B is cut, as shown in fig. 4, and the edges *m* and *n* thereof form, with the edges from *d* to *e* on the front piece A, the upright seam, as shown in fig. 1.

The backs of the quarters or side pieces B and C are sewed together, from the bottom to the top of the counter, the rest of the back being provided with lace, buckles, buttons, or other suitable device for fastening together.

We are aware that cutting the shoe open at the rear and lacing it up is not new.

Having thus fully described our invention, what we claim as new, and desire to secure by Letters Patent, is—
The front piece A and side pieces B and C, formed in the manner described, for the purpose of forming a shoe, substantially as and for the purposes herein set forth.

In testimony that we claim the foregoing, we have hereunto set our hands, this 12th day of May, 1868.

JAMES S. LESTER,
PERRIN H. CARDWELL.
